UNITED STATES PATENT OFFICE.

LOUIS A. HOERR, OF ST. LOUIS, MISSOURI.

DRAFT-RIGGING.

SPECIFICATION forming part of Letters Patent No. 774,388, dated November 8, 1904.

Application filed April 28, 1904. Serial No. 205,295. (No model.)

To all whom it may concern:

Be it known that I, LOUIS A. HOERR, a citizen of the United States, residing at the city of St. Louis, in the State of Missouri, have invented a certain new and useful Draft-Rigging, of which the following is such a full, clear, and exact description as will enable any one skilled in the art to which it appertains to make and use the same, reference being had to the accompanying drawings, forming part of this specification.

My invention relates to draft-rigging for railway-cars, and more particularly to that form of draft-rigging known as "tandem" draft-rigging, in which two or more draft-springs are arranged in the rigging in tandem relation.

One of the main objects of my invention is to dispense with the use of draw-bar straps and tail-bolts in the above-described class of draft-rigging, whereby the parts are more readily removed and placed in position than in the form of draft-rigging heretofore used. This construction also allows of greater angular lateral movement of the draw-bar, and consequently the draw-bar can more readily accommodate itself to the direction of the thrust or pull when the cars are rounding a curve.

My invention consists in various novel features and details of construction, all of which are described in the following specification and pointed out in the claims affixed hereto.

In the accompanying drawings, which illustrate a draft-rigging made in accordance with my invention, together with a portion of a car to which the same is attached, Figure 1 is a vertical longitudinal section. Fig. 2 is a top plan view of the rigging removed from the car. Fig. 3 is a side elevation of one of the draft-sills looking at the inside of the sill. Fig. 4 is a view similar to Fig. 3 looking at the outside of the sill. Fig. 5 is a horizontal longitudinal section through the rigging. Fig. 6 is a section on the line 6-6 of Fig. 5, and Fig. 7 is a section on the line 7-7 of Fig. 5.

Like marks of reference refer to similar parts in the several views of the drawings.

10 is the car-decking, 11 the end sills, 12 the sheathing, 13 the dead-wood, 14 the coup-

ler-bearing, 15 the body-bolster, and 16 the center sills, all of which may be of any ordinary construction.

Secured to the lower edges of the center sills 16 are the draft-sills 17. These draft-sills 17 are made of metal and are secured to the center sills by bolts 18 passing through the said center sills and through lugs 19 on the draft-sills. Arranged between the draft-sills 17 is the draw-bar 20, provided with the usual coupler-head 21. Passing through the draw-bar 20 is a key 22. This key 22 also passes through an elongated slot 23 in the forward end of the draft-sills 17. The rear end of the draw-bar 20 bears against a follower-plate 24. This follower-plate 24 is provided with guides 25, formed on the inner surfaces of the draft-sills 17, and with stops 26, which limit the forward movement of the said follower-plate. Resting against the follower-plate 24 is a draft-spring 27, the opposite end of which rests against the forward end of a spring-pocket 28. Within the spring 27 is an auxiliary spring 29. The spring 27 is held against falling from between the parts 24 and 28 by means of a cross-bar 30, bolted to lugs 31, carried on the draft-sills 17. The spring 27 is prevented from upward movement by a short hood 32, carried by the spring-pocket 28. Passing through the spring-pocket 28 is a follower-plate 33, situated within the spring-pocket 28, and at the rear of the follower-plate 33 is a main draft-spring 34 and an auxiliary draft-spring 35. Passing through the spring-pocket 28 in front of the follower-plate 33 is a key 36. This key 36 passes between a pair of guides 40. The keys 22 and 36 are connected outside of the draft-sills 17 by means of connecting bars or links 39. The follower-plate 33 is held in position by guides 37 on the draft-sills 17, and its forward movement is limited by a stop 41. The guides 37 and stop 41 are similar to the guides 25 and the stops 26 hereinbefore described. The key 36 also passes through a slot 42 in the draft-sills 17, similar to the slot 23, through which the key 22 passes. The rearward movement of the spring-pocket 28 is limited either by a timber block 43, placed between the end of the said spring-pocket and the body-bolster 15, as

shown in Figs. 1 and 2, or by stops 44, formed on the draft-sills 17, as shown in Figs. 3 and 5. 45 represents bolts passing through lugs 46 on the draft-sills 17 and anchoring the said 5 draft-sills to the body-bolster 15. The spring-pocket 28 is partially supported by the key 36. In order to more firmly support the same in position, however, I provide a cross-bar 47, bolted to lugs 48 on the draft-sills 17.

10 The operation of my rigging is as follows: When the draw-bar 20 is drawn forward, its movement is communicated, through the key 22 and connecting-bars 39, to the key 36. The forward movement of the key 36 carries the 15 spring-pocket 28 forward, and as the forward movement of the follower-plate 24 is limited by the stops 26 the springs 27 and 29 are compressed. At the same time the springs 34 and 35 are compressed between the follower-plate 20 33 and the rear end of the spring-pocket. The 25 compression of the springs through the follower-plates 24 and 33 transfers the strain to the draft-sills 17, and these in turn through the bolts 45 transmit practically the entire strain to the body-bolster 15. In case of a thrust in place of a pull on the draw-bar 20 the springs 27 and 29 are compressed between the forward end of the spring-pocket 28 and the follower-plate 24, because the movement 30 of the spring-pocket to the rear is limited either by the block 43 or by the stops 44 hereinbefore described. At the same time the movement of the draw-bar is transmitted, through the key 22 and connecting-bars 39, to 35 the key 36, and this key by forcing the follower-plate 33 to the rear will compress the springs 34 and 35 between the said follower-plate and the rear end of the spring-pocket.

It will be evident that as there are no draw-bar straps or tail-bolts used in my construction the various parts of the rigging may be readily removed and replaced simply by removing the cross-bars 30 and 47 and the keys 22 and 36, and at the same time the absence 45 of these draw-bar straps and tail-bolts allows great angular movement of the draw-bar, so that the draw-bar can accommodate itself to the direction of a pull or thrust in passing around curves. My construction is also such 50 that nearly the entire thrust or pull is transferred to the body-bolster.

Having fully described my invention, what I claim as new, and desire to secure by Letters Patent of the United States, is—

55 1. In a draft-rigging, the combination with a draw-bar, of draft-sills, a pair of draft-springs between said sills, a key passing through said draw-bar and draft-sills, a second key passing through said draft-sills and 60 between said springs, and connections between said keys.

2. In a draft-rigging, the combination with a draw-bar, of draft-sills, a pair of draft-springs between said sills, a key passing 65 through said draw-bar and draft-sills, a sec-

ond key passing through said draft-sills and between said springs, and connections outside of said draft-sills between said keys.

3. In a draft-rigging, the combination with a draw-bar, of draft-sills, a spring-pocket 70 between said draft-sills, a spring in said spring-pocket, a key passing through said spring-pocket, a key passing through said draw-bar, and connections between said keys.

4. In a draft-rigging, the combination with a draw-bar, of draft-sills, a spring-pocket 75 between said draft-sills, a follower passing through said spring-pocket, a spring in said pocket at one side of said follower, a key passing through said spring-pocket at the other side of said follower, and connections between 80 said key and draw-bar.

5. In a draft-rigging, the combination with a draw-bar, of draft-sills, a spring-pocket 85 between said draft-sills, a follower passing through said spring-pocket, a spring in said pocket at one side of said follower, a key passing through said spring-pocket at the other side of said follower, a key passing through 90 said draw-bar, and connections between said keys.

6. In a draft-rigging, the combination with a draw-bar, of draft-sills, a draft-spring between said sills, a spring-pocket bearing against said spring, a second spring within 95 said spring-pocket, a key passing through said spring-pocket, a key passing through said draw-bar, and connections between said keys.

7. In a draft-rigging, the combination with a draw-bar, of draft-sills, a spring-pocket, a spring between said draw-bar and spring-pocket, a second spring in said spring-pocket, a key passing through said pocket, a key passing through said draw-bar, and connections between said keys. 100

8. In a draft-rigging, the combination with a draw-bar, of draft-sills, a spring-pocket, a follower against which said draw-bar bears, a spring between said follower and said spring-pocket, a follower passing through said spring-pocket, a second spring in said spring-pocket at one side of said follower, a key passing through said spring-pocket at the other side of said follower, a key passing through 110 said draw-bar, and connections between said keys. 115

9. In a draft-rigging, the combination with a draw-bar, of draft-sills, a spring-pocket, a spring between said draw-bar and spring-pocket, a hood carried by said spring-pocket for preventing the upward movement of said spring, a second spring in said spring-pocket, a key passing through said spring-pocket, and connections between said key and draw-bar. 120

10. In a draft-rigging, the combination with a draw-bar, of draft-sills, a spring-pocket, a spring between said draw-bar and spring-pocket, a hood carried by said spring-pocket for preventing the upward movement of said spring, a second spring in said spring-pocket, a key passing through said spring-pocket, a 125 key passing through said spring-pocket, a 130

key passing through said draw-bar, and connections between said keys.

11. In a draft-rigging, the combination with a draw-bar, of draft-sills, a spring-pocket, a follower against which said draw-bar bears, stops limiting the forward movement of said follower, a second follower passing through said spring-pocket, stops limiting the forward movement of said second follower, a spring in said spring-pocket, a second spring between said spring-pocket and said first follower, and means for limiting the rearward movement of said spring-follower.

12. In a draft-rigging, the combination with a draw-bar, of draft-sills, a spring-pocket, a follower against which said draw-bar bears, stops limiting the forward movement of said follower, a second follower passing through said spring-pocket, stops limiting the forward movement of said second follower, a spring in said spring-pocket, a second spring between said spring-pocket and said first follower, a bolster, and a block extending from said bolster to said spring-pocket for limiting the rearward movement of the latter.

13. In a draft-rigging, the combination with a car-body, of a body-bolster, draft-sills carried by said car-body and terminating at a distance in front of said body-bolster, anchor-bolts spanning the space between said draft-sills and body-bolster and anchoring the former to the latter, a draw-bar, and spring connections between said draw-bar and draft-sills.

14. In a draft-rigging, the combination with a car-body, of a body-bolster, draft-sills carried by said car-body and terminating at a distance in front of said body-bolster, lugs carried on the outside of said draft-sills, anchor-bolts spanning the space between said lugs and body-bolster and thereby anchoring said draft-sills to said body-bolster, a draw-bar, and spring connections between said draw-bar and draft-sills.

In testimony whereof I have hereunto set my hand and affixed my seal in the presence of the two subscribing witnesses.

LOUIS A. HOERR. [L. S.]
